UNITED STATES PATENT OFFICE.

WILLIAM H. PENROSE, OF THE UNITED STATES ARMY.

SAW-FILING MACHINE.

SPECIFICATION forming part of Letters Patent No. 409,866, dated August 27, 1889.

Application filed November 17, 1888. Serial No. 291,111. (No model.)

To all whom it may concern:

Be it known that I, WILLIAM H. PENROSE, an officer in the United States Army, stationed at Fort Douglass, in the Territory of Utah, 5 have invented certain new and useful Improvements in Saw-Filing Machines; and I do hereby declare that the following is a full, clear, and exact description thereof, reference being had to the accompanying drawings, and 10 to the letters of reference marked thereon, which form a part of this specification.

This invention relates to devices for filing saws of that class comprising a support for a reciprocating file-frame and a guiding-connection 15 of the file-frame with the support.

One object of the improvements herein described and claimed is to provide a construction by which the necessity of employing a vise or long wooden clamps to hold the saw is 20 obviated; and to this end the device contains a saw-clamp with which the file-frame has a direct guiding-connection.

Other objects of the invention have reference to adjustments whereby the angle of the 25 tooth-faces may be varied, the distance between tooth-points may be determined, and the depth of the file-cut regulated; and to these ends the invention consists in features of construction, which are hereinafter fully 30 explained.

Referring to the accompanying drawings, Figure 1 is a perspective view of the complete device applied to a saw, a central portion of the file being broken out to better reveal portions which would otherwise be in part hidden thereby. Fig. 2 is a top view of the saw-clamp and its immediate attachments, the file-frame being removed. Fig. 3 is a transverse section of the saw-clamp in the line 3 3 of 35 Fig. 2, looking in the direction of the arrows applied to said line.

A represents a saw-clamp consisting of an oblong metal frame slotted deeply from the under side to rest over the edge of a saw-blade, the slot being sufficiently wide and deep to accommodate a wooden gab or clamp jaw A', arranged to bear on one side of the saw-blade and forced against the saw by means of a set-screw A², which is threaded through the 45 50 adjacent flange of the clamp.

A³ is a strip of wood or other similar mate-

rial occupying the bottom of the slot in the saw-clamp to rest on the points of the teeth to prevent the latter from being dulled by contact with the metal of the clamp. 55

A⁴ is a notch cut away in the back of the saw-clamp to allow the file to reach the teeth or saw-edge, the clamp A thus having bearing and support upon the edge of the saw at both sides of the point at which the file works 60 thereon. Upon one end of the clamp A is pivoted a turn-block B by a pivot b, arranged in the immediate plane of the saw-blade. This turn-block is provided with a vertical back piece or bracket B', to which is pivoted a sec- 65 ond turn-block C by a pivot c, also in the plane of the saw-blade. The turn-block B is provided with a curved slot b', formed in the arc of a circle drawn from the axis of the pivot b, and through this slot passes the shank of a 70 clamp-screw b², which screws into the back of the clamp A. The turn-block C has a similar slot c', through which passes a similar clamp-screw c², which screws into the bracket B'. 75

The letter D designates the file-frame as a whole, said frame consisting of two parallel end bars D' D², joined by the rods D³ and D⁴, the first of which connects corresponding ends of the end bars and forms the back of the file-frame and the second of which connects points of the end bars intermediate to their extremities. The turn-block C is provided at its opposite ends with projecting arms C' C², through which are formed holes for the passage of the rod D³ to the file-frame, 80 thus forming a guide for said file-frame in its reciprocating movement. 85

To the end bar D' of the file-frame nearest the operator is applied a handle D⁵, by which the frame is reciprocated, and between the 90 free ends of the end bars D' and D² is removably inserted the file E. For this purpose a hole for the reception of the shank e of the file is provided in the end bar D', and the opposite end of the file is thrust into a 95 socket-piece E' in the free end of the opposite frame-bar D². The socket-piece E' is desirably a separate part inserted in a hole in the end of the bar D², so that it may both rotate and slide longitudinally in the end bar 100 and is held in any desired position by means of a set-screw d. To insert or remove the

file when the socket-piece is thus constructed, the set-screw d is retracted and the socket-piece slid away from the file, which releases the adjacent end of the latter and allows the 5 file-shank to be drawn forward out of the hole or socket in the corresponding end of the opposite bar D' . The outer end bar D^2 of the file-frame is also desirably secured to the parallel rods D^3 and D^4 by set-screws d' 10 and d^2 , so that the entire end bar may be moved on the rods with a view of adjusting the distance between the end bars to files of different lengths. The file may also be released by loosening the set-screws d' and d^2 15 instead of by giving a longitudinal movement to the socket-piece E' , if preferred, and in that case the socket-piece E' need not have a longitudinal movement in the end of the bar D^2 unless preferred.

20 The guiding-rod D^3 is held at both its ends by set-screws d' , so that said rod is removable when it shall have been worn to permit a new one to be inserted.

25 The rod D^4 of the file-frame co-operates with an adjustable stop in the saw-clamp for the purpose of automatically adjusting the depth to which the file E shall cut. The stop on the clamp consists, as here shown, of a screw F , which passes into a boss on the 30 back of the clamp-frame immediately beneath the rod D^4 and in the plane of the saw-blade, so that when the file E has reached the proper depth said rod will strike the top or head of the screw F and prevent further entrance of the file. The stop-screw F is held 35 firmly in its position against disturbance by contact with the rod or otherwise by means of a set-nut F' .

40 For the purpose of adjusting the width of the teeth or the distance between their points, a gage G is provided on the saw-clamp at the notch A^4 and extends down into engagement with a tooth of the saw already cut. This gage G is a plate of steel brought to an edge on 45 its lower extremity and secured by a set-screw g to the vertical arm h of a bracket H . The bracket H is movable lengthwise of the back of the saw-clamp, to which end it is provided with a slot h' , through which passes a clamp-screw h^2 , that enters the back of the clamp.

50 The operation of the device thus described is obvious. In refiling a saw, the saw-clamp A being fastened upon the saw-blade by means of the set-screw A^2 , with the gage G 55 bearing against the front face of a tooth al-

ready cut and the file depressed in a notch between two other teeth, the bracket H is secured by the screw h^2 . The file-frame D being reciprocated by the operator, the file E will deepen the notch in which it rests to a 60 depth determined by the position of the stop-screw F , and the angle of the file with respect to the saw-blade in either direction will be determined by the positions given to the several turn-blocks B and C . The presence of the gage 65 G insures that the tooth-point being sharpened by the file shall be at a given distance in advance of that engaged by the gage, and this results inevitably in the equal spacing of the toothed points. After a tooth has been sharpened, the clamp is released and refastened to the saw-blade with the gage G set in the next tooth-notch, and so on till the saw has been filed throughout its length. In cutting teeth originally the gage G is set at a distance from 70 the file equal to the aggregate width of two, three, or more teeth of the width desired to be given them.

I claim as my invention—

1. The combination, with a saw-clamp, a 80 file-frame, and a guide for the frame attached to the clamp, of an adjustable stop on the clamp which engages the frame and regulates the depth of the cut.

2. The combination, with a saw-clamp carrying a reciprocating file-frame, of a gage consisting of a longitudinally-adjustable bracket H and a vertically-adjustable gage-point secured to said bracket, all substantially as described. 85

90 3. The saw-clamp provided with the removable guard-strips of wood or similar material resting on the tooth-points.

4. The combination of the saw-clamp provided with the notch A^4 , turn-block B , having 95 the vertical arm B' , the turn-block C , pivoted to the arm B' , the file-frame D , having a rod D' parallel with the file and running in guides on the turn-block C , and also with the parallel intermediate rod D^3 , the adjustable stop F , 100 the gage-bracket H , secured adjustably to the clamp, and the gage-plate G , secured to the bracket H .

105 In testimony that I claim the foregoing as my invention I affix my signature in presence of two witnesses.

WILLIAM H. PENROSE.
